UNITED STATES PATENT OFFICE.

JOHN L. GAFFNEY, OF CHICAGO, ILLINOIS.

APPARATUS FOR APPLYING ABRASIVE MATERIAL OR PAINT TO THE SURFACE OF MATCH BOXES.

Application filed February 1, 1922. Serial No. 533,338.

To all whom it may concern:

Be it known that I, JOHN L. GAFFNEY, a citizen of the United States, residing at Chicago, in the county of Cook and State 5 of Illinois, have invented certain new and useful Improvements in an Apparatus for Applying Abrasive Material or Paint to the Surface of Match Boxes, of which the following is a specification.

10 This invention relates to improvements in an apparatus more particularly intended for use as an adjunct to, or in connection with, box-making machines of the type employed for making boxes for safety-matches, but 15 may be employed separately from such machines without a departure from the invention.

As is well known to those skilled in the art to which my invention pertains, the 20 boxes for safety-matches, and sometimes those for other kinds of matches, consist each, of an open faced rectangular box or container for the matches and an open ended similarly shaped "shuck" into which the 25 said box is slidably located so that it can be slid in the proper direction to expose either end of the box, to the end, that the matches may be reached for removal and use, or if desired, the box may be entirely removed 30 from its "shuck".

In the boxes for safety-matches, it is desirable that the opposite sides of the "shucks" thereof shall be provided externally with a coating of suitable material or composition, 35 which will co-act with the composition or material out of which the heads of the matches are made, when said heads are rubbed on the coating, to produce ignition, without the danger of flying sparks. In the 40 boxes for other kinds of matches, it is desirable that the opposite sides of each "shuck" thereof shall be provided with an abrasive against which the heads of the matches may be rubbed or struck to create 45 ignition. In either case, the composition or material forming the striking surfaces for the matches, is applied in the form or consistency of paste or glue and is called in the trade, "paint."

50 The principal and general object of the invention is, to provide an apparatus for applying the abrasive material or match-igniting coating to the surfaces of match boxes without the usual manual handling or 55 manipulation of the boxes.

Another object is the provision of a machine of the above mentioned general character, which can readily be operatively connected to a portion of a box-making machine, in such a way that the "shucks" of the boxes 60 discharged from said machine, will be fed forwardly and automatically by the power of said machine, a distance on the guide-bar of the apparatus.

A further object is to provide means 65 whereby the "shucks" will automatically be turned as they travel along the guide-bar therefor, to the end, that first one side thereof may be coated and later the opposite side, and afterwards, to another position as they 70 are discharged.

Other objects and advantages of the invention will be disclosed in the following description and explanation.

The invention consists in certain peculiarities of the construction, novel arrangement and combination of the various parts thereof as will be hereinafter more fully set forth and specifically claimed.

In the accompanying drawings— 80

Fig. 1 is a plan view of the apparatus showing a fragment of the frame of a box-making machine to a part of which machine a member of the apparatus is connected.

Fig. 2 is a view in side elevation of the 85 apparatus.

Fig. 3 is a cross-sectional view taken on line 3—3 of Fig. 1 looking in the direction indicated by the arrows.

Fig. 4 is an enlarged vertical sectional 90 view taken on line 4—4 of Fig. 1 as indicated by the arrows.

Fig. 5 is a detached perspective view of the guide bar for members of the match boxes, and 95

Fig. 6 is an enlarged view in side elevation of a portion of said bar, showing it connected to a similar bar of a box-making machine.

Like numerals of reference refer to corresponding parts throughout the different views of the drawings.

The supporting frame of the apparatus is designated by the reference numeral 10 and is of an elongated rectangular form 105 and supported horizontally by means of legs 11 one of which is located at or near each of the corners of the frame. Mounted on the upper surface of the frame 10 is a platform or table 12 which has transversely 110

journaled thereon near its front and rear ends, driven shafts 13 and 14 respectively, each of which shafts has mounted thereon near one of its ends a sprocket wheel 15, the 5 wheel 15 on the shaft 14 being engaged by a sprocket chain 16 extended around a sprocket wheel 17 on the driving shaft 18 which is transversely journaled on and above the platform 12 between the driven shafts 10 13 and 14 as will be readily understood by reference to Fig. 1 of the drawings.

Mounted on the platform 12 below each of the shafts 13 and 14, is a steam jacketed receptacle or pot designated as a whole by 15 the numeral 19 each of which receptacles is elongated and placed lengthwise with respect to the shaft below which it is located, and transversely with respect to the main frame. The end walls of each of the 20 receptacles or pots 19 are of convenient height to afford journal boxes or bearings for the driven shafts 13 and 14 respectively. As is clearly shown in Figs. 1 and 4 of the drawings, each of the receptacles or pots 25 19 is provided with a cavity 20 which is substantially semi-circular in cross-section and each of said receptacles has communicating with the upper portion of its cavity an auxiliary cavity or chamber 21 which 30 is located about midway between the ends of the receptacle 19 and is formed in a laterally extended enlargement 22 with which each of the receptacles 19 is provided.

As is clearly shown in Fig. 4, each of the 35 receptacles 19 is provided with a cavity or chamber 23 which is located below the main cavity 20 of the receptacle and is used for the passage of a heating agent such as steam, which may be supplied to the chamber 23 40 through a supply pipe 24 having communication with a supply of steam or heat not shown. Leading from the chamber or steam jacket 23 is an exhaust pipe 25 which may lead to any suitable point of discharge. 45 Mounted on each of the shafts 13 and 14 within the cavity 20 of the pot or receptacle thereunder, is a paddle wheel, designated as a whole by the numeral 26, which comprises a series of paddles 29 which extend 50 from each side of the wheel 26 to near the ends of the pots in which they are located and lie in parallelism with one another and the shaft on which the wheel is mounted.

Pivottally mounted outwardly of each end 55 of each of the receptacles 19, and on the shaft extended through said receptacle, is an arm 30 which extends forwardly and rearwardly of the shaft on which each pair of said arms is mounted, it being understood that that end of the main frame 10 adjacent the fragment of the box machine frame 31 is termed the rear end, while the opposite end will be regarded as the front or discharging end of the apparatus. 60

65 Journaled on the front portion of each

pair of the arms 30 is a shaft 32 which carries about midway between its ends a brush wheel 33, which, as is clearly shown in Figs. 1 and 4 of the drawings, consists of a pair of spaced disks 34 and 35, between 70 which disks are mounted radially extended bristles 36 which are adapted to contact with the lower surface of the guide-bar 37 for the "shucks" of the match boxes, but when said boxes are slid along said guide-bar, to contact with the lower surfaces of said "shucks", instead of the bar, as they travel along the guide-bar. These brush wheels are adjustable by means of the arms 30 on which they are journaled, for it will 75 be seen by reference to Fig. 2 of the drawings, that each of said arms carries at its rear end an adjusting screw 38, to contact with an overhanging flange 39 with which each of the pots 19 is provided. By this 80 arrangement it is apparent that by screwing the set screws 38 upwardly the brush wheels 34 will be correspondingly elevated, when by unscrewing said screws, said wheels will be lowered so as to extend deeper 85 into the cavities 21 of the projections 22, which cavities as well as the cavities 20 of the pots, are supplied with a suitable composition or abrasive which it is the function 90 of the wheels 26 and brush wheels to apply 95 to the "shucks" and to smooth or distribute it thereon respectively. The front ends of each pair of the arms 30 are connected together by a brace rod 40. That end of each of the shaft 32 which carry the brush wheels 100 adjacent the sprocket wheels 15 has mounted thereon a pinion 41 each of which meshes with a gear 42 mounted on each of the driven shafts 13 and 14 between the wheels 15 and adjacent ends of the paint pots. 105

Fixed on the driving shaft 18 near the sprocket wheel 17 thereon, is a pulley 43 to which power for operating the apparatus may be applied through a belt 44 leading from a source of power supply, not shown. 110 The driving shaft 18 has mounted thereon near its ends opposite the sprocket wheel 17, another sprocket wheel 45 which is geared by means of a sprocket chain 46 to a sprocket wheel 47 on a shaft 48 transversely journaled on the platform 12 forwardly of the driving shaft. Near the sprocket wheel 45 the driving shaft 18 has mounted thereon a rubber or rubber-tired wheel 49 which contacts lightly with the 115 lower surface of a roller 50 carried by the middle portion of the guide-bar 37, which guide-bar may be connected at its rear end to the front end of a guide-bar 51 of a box making machine, a portion of which latter 120 guide-bar and a fragment of the frame of a box-making machine is shown in Figs. 1 and 2 of the drawings. 125

Transversely located with respect to the frame above the driving shaft 18 is a short 130

shaft 52, which shaft is supported by a substantially U-shaped bracket 53, the arms 54 of which bracket are secured at their lower ends to the platform 12, below the shaft 48 and are inclined rearwardly and upwardly as shown in Fig. 2, in which view it will be observed that the transverse portion 53 of said bracket is supported at one of its ends by an upright 55 resting at its lower end on the platform of the main frame. The opposite end of the transverse portion of the bracket 53 is connected to the platform by means of a spring 56 the tension of which is exerted downwardly on said bracket for the purpose to be presently explained.

Mounted on the shaft 52 carried by the bracket 53 is a rubber or rubber-tired wheel 57, which is located in the same vertical plane with the wheel 49 and roller 50, and impinges lightly against the latter. The shaft 52 also carries a pulley 58 which is preferably of the grooved type. Over this pulley is extended a cross-belt 59 which also extends over a pulley 60 on the shaft 48. This latter pulley is by preference of the grooved type and is fixed to the shaft 48 while the pulley 58 is fixed to the shaft 52. By this arrangement it is manifest that in the rotation of the driving shaft 18, the shaft 48 will be rotated by reason of its connections 45, 46, and 47, with the driving shaft, and in turn the shaft 48 will cause the shaft 52 and the wheel 57 thereon to be rotated.

The auxiliary shaft 48 has mounted thereon directly below the guide-bar 37, a grooved pulley 61 on which the lower surface of said bar will rest. The shaft 48 also has mounted thereon near its end opposite that on which the sprocket wheel 47 is mounted, a pair of sprocket wheels 62 and 63, the former of which has extended there-over a sprocket chain 64 which engages the sprocket wheel 15 on the paddle-wheel-carrying shaft 13 near the front of the supporting frame, and transmits rotary motion to the last named shaft. A sprocket chain 65 is extended over the sprocket wheel 63 and engages a sprocket wheel 66 mounted on the transversely journaled shaft 67 at the front end of the supporting frame, which latter shaft has mounted thereon, a pair of sprocket wheels 68 and 69 over which is extended a slatted endless conveyer 70 which is located directly under the front portion of the guide-bar 37 and is employed to receive the "shucks" of the match boxes flat-wise as they are discharged from the guide-bar.

By the foregoing described arrangement of the parts and the manner in which the shafts of the apparatus are geared together, it is manifest that by applying power to the wheel or pulley 43 on the drive shaft 18, said shaft may be caused to be rotated in the proper direction so as to cause the paddle wheels on the shafts 13 and 14, as well as

the brush wheels 33 on the shafts 32, to be rotated, to the end that the abrasive material or the material with which the opposite sides of the "shucks" are to be coated, to be continuously stirred by the paddles and first applied to the lower surfaces of the "shucks" by the peripheries of the wheels 26, and then distributed or smoothed on said surfaces by the bristles 36 of the rotary brushes 33.

It will be understood that the "shucks" will pass from the guide-bar 51 of the box-making machine, when the latter is employed, onto the guide-bar 37 of the apparatus, in a continuous fashion. That is, the rear end of one of the "shucks" will contact with the front end of the adjacent "shuck" as they pass from the guide-bar 51 of the box-making machine, to the guide-bar 37 of the apparatus, and consequently, they will be fed forwardly on the guide-bar 37 for a considerable distance by the power of the box-making machine, but as soon as the forward-most "shuck" on the guide-bar 37 reaches the wheel 26 rearwardly of the feed wheels 49, 50 and 57, it will be forced forwardly on the guide-bar 37 by the action of said wheel. This operation will be repeated as each of the "shucks" is presented at its front end to said wheels 26 and the feeding wheels, with the result that after they pass forwardly of said wheels, the "shucks" will be caused to travel along the guide-bar 37 by reason of the power imparted to them by said feed wheels, until the "shucks" are discharged from the front end of the guide-bar. The pulley 61 is employed to assist in the forward movement of the "shucks," for it will be understood that said pulley contacts lightly with the lower surface of the guide-bar in order that the lower portion of the "shucks" may pass between said guide-bar and pulley.

A very important feature of the invention is the construction of the guide-bar 37 which is clearly shown in Fig. 5 of the drawings. In this view, as well as in Figs. 1 and 2, it will be noted that the bar 37 is rectangular in cross-section and of greater depth than thickness. This bar is of substantially the same shape as the cavity of the "shucks" of the match boxes, and of sufficient size to fit snugly therein yet in such a manner as to permit the "shucks" to be slid freely thereon. Between its ends the bar 37 is provided with a half-turn twist 37^a, and in the middle of said twisted portion with the roller 50 which is journaled in a suitable opening in the bar and extends slightly through opposite surfaces thereof. Now as the "shucks" travel from the rear end of the bar forwardly thereon, they will present their narrow surfaces in horizontal planes one above the other so that the coating material can be applied to the lower surface of each "shuck" by the wheel 26 and subjected to the action

of the brush wheel 33 of the pot 19, both co-acting with said material in the pot 19 at the rear end of the main frame. After thus having their lower surfaces coated, the "shucks" 5 will be forced forwardly on the twisted portion 37^a of the bar 37, and will thereby be turned one-half of a revolution, thus presenting the formerly upper surface of each "shuck" downwardly to be subjected to the 10 application of the coating material by the wheel 26 and brush wheel 33 in the pot 19 located near the front end of the main frame. As the "shucks" travel along the twisted portion 31^a of the guide-bar it is 15 manifest that when they reach the middle portion of said twisted part, their narrow sides will be presented in vertical planes, and that the tops and bottoms of the "shucks" will pass between the feed wheel 20 57 and roller 50 on the guide-bar and between the roller 50 and the feed wheel 59 respectively, and thereby be pressed towards the bar and be fed forwardly thereon.

In order to heat the coating material in 25 the pots 19 so as to obtain and maintain the proper consistency thereof, I provide each of them with a steam or heat chamber 23 to which heat may be supplied through the pipe 24 and exhausted through the pipe 25 30 of each pot. By employing the spring 56 it is manifest that the feed wheel 57 will be more or less yieldingly supported so that its contact with the "shucks" will be such as to cause the same to be fed forwardly by the 35 said wheel on the guide-bar. The discharging end of the guide-bar 37 has extended therefrom a pair of oppositely-bent wires 71 and 72 which are the equivalent of the side edges of a portion of the twisted part of said 40 bar. These wires or short rods are so bent as to turn the "shucks" as they are discharged from the bar one-quarter of a turn, with the result that the "shucks" will be righted or positioned to fall with their broad sides on 45 the slats of the endless conveyor 70 which is employed to carry the "shucks" to any desired point for deposit. By means of the adjustable arms 30 and their adjusting screws 38, it is manifest that the brush 50 wheels 33 can be positioned with respect to the guide-bar 37 so as to regulate the action of the bristles 36 of said wheels so as to render the coating thin or thicker as may be desired. 55 Having thus fully described my invention, what I claim as new and desire to secure by Letters Patent is—

1. In an apparatus of the class described, the combination with a supporting frame, of 60 a guide-bar located longitudinally above the same and having a half-turn twist intermediate its ends, said bar being adapted for travel longitudinally thereon of hollow open-ended members, rotary means above

and below the said bar for pressing opposite 65 portions of said members towards said bar and forwardly on the same.

2. In an apparatus of the class described, the combination with a supporting frame, of a cross-sectionally rectangular guide-bar located longitudinally above the same and having a half-turn twist intermediate its ends, said bar adapted for travel longitudinally thereon, of hollow open-ended members which follow the form of the bar and 70 whereby said members will be turned one-half of a complete revolution, and rotary means above and below said bars for pressing opposite portions of said members towards said bar and forwardly on the same. 80

3. In an apparatus of the class described, the combination with a supporting frame, of a guide-bar located longitudinally above the same and having a half-turn twist intermediate its ends, said bar adapted for travel 85 longitudinally thereon of hollow open-ended members, rotary means above and below said bar between the ends of its said twist for pressing opposite portions of said members towards said bar and forwardly on the same. 90

4. In an apparatus of the class described, the combination with a supporting frame, of a guide-bar located longitudinally above the same and having a half-turn twist intermediate its ends and a one-fourth-turn twist 95 at its discharging end, said bar being adapted for travel longitudinally thereon of hollow open-ended members, rotary means above and below the said bar for pressing opposite portions of said members towards 100 said bar and forwardly on the same.

5. In an apparatus of the class described, the combination with a supporting frame, of a guide-bar located longitudinally above the same and having a half-turn twist intermediate its ends, a roller journaled in a suitable opening in the bar at the middle of its twist, said bar being adapted for travel longitudinally thereon of hollow open-ended members, rotary means above and below the 110 said roller on said bar for pressing opposite portions of said members towards said roller and forwardly on the bar. 105

6. In an apparatus of the class described, the combination with a supporting frame, 115 of a guide-bar located longitudinally above the same and having a half-turn twist intermediate its ends, said bar being adapted for travel longitudinally thereon of hollow open-ended members, rotary means above and 120 below said bar for pressing opposite portions of said members towards said bar and forwardly on the same, means rearwardly and forwardly of said rotary means for applying a coating of suitable material to the 125 lower surfaces of said members in their progress along said bar, and means at the free end of said bar for righting said mem-

bers as they are discharged from the bar.

7. In an apparatus of the class described, the combination with a supporting frame, of a guide-bar located longitudinally above the same and having a half-turn twist intermediate its ends, said bar being adapted for travel longitudinally thereon of hollow open-ended members, rotary means above and below said bar for pressing opposite portions of said members towards said bar and forwardly on the same, means rearwardly and forwardly of said rotary means for applying a coating of suitable material to the lower surfaces of said members in their tracks along said bar.

8. In an apparatus of the class described, the combination with a supporting frame, of a cross-sectionally rectangular guide-bar located longitudinally above the same and having a half-turn twist intermediate its ends, said bar being adapted for travel longitudinally thereon of hollow open-ended members, rotary means above and below said bar for pressing opposite portions of said members towards said bar and forwardly on the same, means rearwardly of said rotary means for applying and distributing a coating of suitable material to and on the lower surfaces of said members, and means forwardly of said rotary means for applying and distributing a coating of suitable material to and on the lower surfaces of said members and in their travel along said bar.

35 9. In an apparatus of the class described, the combination with a supporting frame, of a cross-sectionally rectangular guide-bar located longitudinally above the same and having a half-turn twist intermediate its ends, said bar being adapted for travel longitudinally thereon of hollow open-ended members, rotary means above and below said bar for pressing opposite portions of said members towards said bar and forwardly on the same, means rearwardly of said rotary means for applying and distributing a coating of suitable material to and on the lower surfaces of said members, means forwardly of said rotary means for applying and distributing a coating of suitable material to and on the lower surfaces of said members in their travel along said bar, and means at the free end of said bar for righting said

members as they are discharged from the bar.

55

10. In an apparatus of the class described, the combination with a supporting frame, of a cross-sectionally rectangular guide-bar located longitudinally above the same and having a half-turn twist intermediate its ends, said bar being adapted for travel longitudinally thereon of hollow-open-ended members, a rotatable wheel mounted above said bar and a rotatable wheel mounted below said bar for clamping opposite portions of said members towards the bar and for forcing them forwardly on the same, a pot or receptacle mounted on the supporting frame rearwardly of said upper and lower wheels, a wheel journaled in said pot and located directly below said bar adapted to approximate the lower surface thereof, a brush wheel journaled in said pot directly under said bar for contact therewith, a pot or receptacle mounted on the supporting frame forwardly of said upper and lower wheels, a wheel journaled in the last named pot and located directly under the bar adapted to approximate the lower surface thereof, a brush wheel journaled in said last named pot directly under said bar for contact therewith, and means for driving all of said wheels and the said brushes simultaneously and in a direction to force the said open-ended members forwardly on said bar.

85

11. An apparatus of the class described including a cross-sectionally rectangular guide-bar having a half-turn twist intermediate its ends and adapted for the travel longitudinally thereon of open-ended members whereby said members will be automatically rotated one-half of a turn consecutively as they progress forwardly on the bar, and means for feeding said members forwardly on the bar.

90

12. An apparatus of the class described including a cross-sectionally rectangular guide-bar having a half-turn twist intermediate its ends and a quarter-turn twist at its discharging end, said bar adapted for the travel longitudinally thereon of open-ended members, and means co-acting with said members to move them forwardly on said bar.

95

JOHN L. GAFFNEY.
